UNITED STATES PATENT OFFICE.

ROBERT B. KILLGORE, OF SHORT HILLS, NEW JERSEY, ASSIGNOR TO STRAUSE GAS IRON CO., OF PHILADELPHIA, PENNSYLVANIA, A CORPORATION OF PENNSYLVANIA.

SELF-HEATING SAD-IRON.

1,112,916.

Specification of Letters Patent.

Patented Oct. 6, 1914.

Application filed November 13, 1912. Serial No. 731,044.

To all whom it may concern:

Be it known that I, ROBERT B. KILLGORE, a citizen of the United States, and a resident of Short Hills, county of Essex, State of New Jersey, have invented certain new and useful Improvements in Self-Heating Sad-Irons, of which the following is a specification.

My invention relates to self heating sad irons in which gas or a similar fuel is the heat producing medium and has for its object to construct an iron of this kind in a manner to secure a maximum of efficiency with a minimum expenditure of fuel.

My invention will be fully described hereinafter and the features of novelty will be pointed out in the appended claims.

Reference is to be had to the accompanying drawings in which—

Figure 1 is a central longitudinal section of my improved sad iron; Fig. 2 is a horizontal section thereof on the line 2—2 of Fig. 1; and Fig. 3 is a cross-section on the line 3—3 of Fig. 1.

In the drawings, 5 represents the hollow body of the iron which may be of any customary and well known shape and in the example shown is provided with a movable cover 6 pivotally connected to said body at the front end thereof as indicated at 7. The said cover 6 is provided at its rear end with a preferably open ended slot 8 for the accommodation of the screw-threaded stem 9 of a locking lever 10, which stem 9 screws into a screw-threaded aperture 11 formed in the rear wall of the body 5. The lever 10 is provided with shoulders 12 adapted to bear upon the cover 6 at opposite sides of the slot 8, when said lever extends transversely of said slot in the position illustrated in Figs. 1 and 3, and thus lock said cover against movement relatively to the body 5. A handle 13 of any suitable description for manipulating the iron and moving the cover is secured to said cover 6 for instance by means of screws 14. The upper edges of the side walls and rear wall of the body 5 are cut away so that when the cover 6 is in its operative position, openings 15 and 16 are formed respectively at the sides and rear of said body for the purpose of promoting a circulation of air within said body and of permitting the products of combustion to readily escape. A channel 17 is formed in the bottom 18 of the body 5 so as

to extend lengthwise thereof and is periodically interrupted by partitions 19 which project across said channel and divide the same into what might be termed a series of independent recesses, said partitions in the example shown being formed integral with the bottom of the body, although this is not absolutely necessary, it being clearly apparent that said independent recesses may be of any desired shape. Air inlets 20 extend through the bottom 18 and have their outer or inlet ends in communication with the atmosphere and their inner or outlet ends in connection with said channel 17 and below the interior surface of the bottom 18, the drawings illustrating a pair of inlets 20 connected with each recess of said channel 17, this arrangement being only an instance and not indispensable.

A burner comprising a tube 21 extends through an opening in the rear wall of the body 5 and has its forward end secured in the front of said body in any suitable manner, as for instance by screw-threading. This tube 21 is located above and in registry with the channel 17 and is provided with jet openings 22 directed toward the bottom 18 in opposite directions as shown best in Fig. 3 and further forms part of or is connected with a mixing tube 23 located externally of said body and preferably extending at an angle to the vertical. The said mixing tube 23 is provided with the usual air inlets 24 and nipple 25, the latter for the accommodation of the customary flexible tube adapted for connection with a source of fuel supply.

When it is desired to use the iron, the said flexible tube is first connected therewith and with the source of fuel supply after which the locking lever 10 is swung to a position parallel with the slot 8, in which condition the shoulders 12 have been raised owing to the coöperation of the threaded stem 9 and aperture 11 and have been moved out of engagement with said cover. The cover 6 is now free to be swung to an open position to expose the interior of the body 5, it being understood that the slot 8 is wide enough to pass the shoulders 12 and lever 10 in the described position without interference. A match, taper or other igniting medium may now be introduced into the interior of the body to ignite the fuel which it is to be understood now issues from the jet openings 110

22 of the burner 21. Owing to the fact that these jet openings 22 are directed toward the bottom 18 in opposite directions the resulting flames will contact with the surface 5 thereof at opposite sides of the channel 17 and will quickly bring said bottom to the heated condition required for use. At the same time, atmospheric air will enter through the air inlets 20 and will pass from 10 opposite sides into the various recesses composing the channel 17 and will then pass through each flame so as to bring about a maximum and perfect combustion of the fuel issuing from said jet openings 22. The 15 products of combustion will pass out of the openings 15 and 16 at the top of the body so that a continuous and complete circulation is secured within said body. During this operation the partitions 19 serve to conduct 20 the heat from one side of the bottom to the other and vice versa, particularly at those points thereof which may be between flames and not directly engaged thereby so that the heating effect is increased and a maximum 25 and evenly distributed heating of the iron is secured with a minimum expenditure of fuel.

It is to be understood that the various parts of the iron itself as well as the burner 30 may be of any general construction and that the illustration is only an example of my improvement and further that the various changes may be made therein within the scope of the claims without departing from 35 the spirit of my invention.

I claim:

1. A sad iron comprising a hollow body.

having a solid bottom provided with air inlet channels extending transversely through said solid bottom toward the center thereof 40 and a plurality of independent recesses commencing at the inner surface of said bottom and extending downwardly therein into connection with said air inlet channels and a burner adapted for connection with a source of fuel supply located in said body in registry with and above said recesses, the space between said burner and the inner surface of said bottom being entirely free throughout 50 its length.

2. A sad iron comprising a hollow body having a solid bottom provided with air inlet channels extending transversely through said solid bottom toward the center thereof and a row of independent recesses 55 commencing at the inner surface of said bottom and extending downwardly therein into connection with said air inlet channels, said row of recesses being located along the longitudinal median line of the body, and a burner adapted for connection with a source of fuel supply located in said body in registry with and above said recesses, the space between 60 said burner and the inner surface of said bottom being entirely free throughout its 65 length.

In testimony whereof I have hereunto set my hand in the presence of two subscribing witnesses.

ROBERT B. KILLGORE.
